PLAYGROUND SWING SUPPORT ADAPTER

Robert S. Wormser, Hillsdale, Mich., assignor to Game-Time, Inc., Litchfield, Mich., a corporation of Michigan

Filed Aug. 13, 1968, Ser. No. 13,124

Term of patent 14 years

Int. Cl. D21—03

U.S. Cl. D34—5

FIG. 1 is a perspective view of the playground swing support adapter constructed in accord with my new design, playground apparatus with which the adapter is employed being shown in dotted lines for illustrative purposes only.

FIG. 2 is an elevational front view of an adapter in accord with my new design, the rear view being identical thereto,

FIG. 3 is an outer end view of the design,

FIG. 4 is an inner end view, as taken from the left of FIG. 2, and

FIG. 5 is a bottom view of my new design.

The characteristic feature of my design resides in the combination of a tubular hand grip sleeve integrally united with a plate in the particular configuration shown.

I claim:

The ornamental design for a playground swing support adapter, substantially as shown and described.
